UNITED STATES PATENT OFFICE.

JOSEPH GODDARD, OF ROCHESTER, NEW YORK, ASSIGNOR TO SENECA CAMERA MANUFACTURING COMPANY, OF ROCHESTER, NEW YORK, A CORPORATION OF NEW YORK.

DESIGN FOR A FOLDING CAMERA.

48,622.

Specification for Design.

Patented Feb. 22, 1916.

Application filed September 16, 1915. Serial No. 51,101. Term of patent 7 years.

To all whom it may concern:

Be it known that I, JOSEPH GODDARD, a citizen of the United States, residing at Rochester, in the county of Monroe and State of New York, have invented a new, original, and ornamental Design for a Folding Camera, of which the following is the specification, reference being had to the accompanying drawing, forming a part thereof.

The drawing is a front elevation of a folding camera showing the novel design hereinbefore referred to.

I claim:—

The ornamental design for a folding camera as shown.

JOSEPH GODDARD.

Witnesses:

M. C. WUEST,

M. F. CONSLER.
